188,540

MAGNETIC TAPE APPARATUS

Frank T. Walsh and Francis A. Farey, Palo Alto, Calif.,
assignors to Ampex Corporation, Redwood City, Calif.,
a corporation of California

Filed July 29, 1959, Ser. No. 56,986

Term of patent 14 years

(Cl. D26—14)

FIG. 1

Des. 188,540

PAGE 2

FIG.4

FIG.2

Des. 188,540

PAGE 3

FIG. 3

FIG. 5

Figure 1 is a front elevational view of a magnetic tape apparatus, showing our new design;

Figure 2 is a side elevational view;

Figure 3 is a rear elevational view;

Figure 4 is a top plan view; and

Figure 5 is a perspective view thereof.

Portions of Figure 1 are diagonally lined to indicate transparency.

We claim:

The ornamental design for a magnetic tape apparatus, substantially as shown and described.
